UNITED STATES PATENT OFFICE.

BAYARD E. TAYLOR, OF OAK PARK, ILLINOIS.

LOCK FOR AUTOMOBILE-DOORS.

1,246,490.

Specification of Letters Patent.

Patented Nov. 13, 1917.

Application filed October 9, 1916. Serial No. 124,687.

To all whom it may concern:

Be it known that I, BAYARD E. TAYLOR, a citizen of the United States, and a resident of the village of Oak Park, in the county 5 of Cook and State of Illinois, have invented certain new and useful Improvements in Locks for Automobile-Doors; and I do hereby declare that the following is a full, clear, and exact description of the same, reference 10 being had to the accompanying drawings, and to the numerals of reference marked thereon, which form a part of this specification.

This invention relates to an improved 15 form of automobile lock, although of course, the lock is adapted for use for many other purposes, wherein it serves to latch a metal strap member, which is connected upon the door jamb or frame and may be locked in 20 position under stress, which may be adjusted at will, so that the door is held tightly closed, free from rattling, in its frame; and furthermore, by changing the relation of said sliding strap member, with 25 a locking mechanism, the door may be positively held at various degrees of opening, for purposes of ventilation, when used where such is desirable.

It is an object therefore of this invention 30 to construct an automobile doorlock embracing a flexible member adapted for hinged connection to the door frame and having sliding relation with a lock mechanism on the door which is constructed to interlock 35 therewith, latching the door closed with said member stressed under tension, so that the door is held closely secured and free from rattling.

It is also an object of this invention to 40 construct a door locking device comprising a flexible strap member having sliding engagement with an interlocking mechanism which operates under spring stress to latch therewith and automatically draw the door 45 tightly closed.

It is also an object of this invention to 50 construct a door locking device embracing a rotatable handle positioned to actuate latching mechanism which automatically interlocks with a flexible strap member having 55 slideable engagement with the device and connected to the frame on which the door is mounted, and constructed to impose stress upon the same after latching therewith, to draw the door upon which the device is attached, closely into its frame.

It is furthermore an object of this invention to construct a door locking device embracing a casing with a handle member rotatably mounted thereon and operable 60 against the stress of a spring impelled rack to which it is geared, and connected to operate an eccentric latching member adapted to latch with means which is attached to the frame on which the door is mounted and 65 after latching therewith, to draw the same under tension to final locked position from which it cannot be moved without proper manipulation of the operating handle.

It is finally an object of this invention to 70 construct an improved type of door lock involving the use of a flexible metal strap member adapted to be interlocked with mechanism attached upon the door, in different adjusted positions with respect thereto to 75 lock the door in either open or closed position, and when interlocked with said mechanism, to fasten the door in closed position under stress, positively secured and free 80 from rattling.

The invention (in a preferred form) is illustrated in the drawings and hereinafter more fully described.

On the drawings:

Figure 1 is a horizontal section taken 85 through a door equipped with a locking device embodying the principles of my invention, and showing the operation in dotted lines.

Fig. 2 is a front face view of the lock 90 detached from the door, and with parts shown in section.

Fig. 3 is an interior plan view of the rear half of the lock casing, showing the bottom slide plate of the construction as well as the 95 eccentrically operated latching member.

Fig. 4 is a detail sectional view taken on line 4—4, of Fig. 2.

Fig. 5 is an exterior plan view of the lock mechanism, with parts in locked position. 100

Fig. 6 is a similar view, illustrating the position of the parts in the initial release movement of the lock.

Fig. 7 is a view similar to Fig. 6, illustrating the position of the parts as the lock 105 is moved into complete release position, and so held against spring stress.

Fig. 8 is a view similar to Fig. 7, illustrating the parts of the locking mechanism after the lock has been released, and showing the 110 operation just prior to the automatic latching of the lock as the flexible strap lock

member moves into latching engagement with the locking latch means.

Fig. 9 is a transverse section taken on line 9—9, of Fig. 5, but with the cover plate 5 attached.

Fig. 10 is a sectional detail taken on line 10—10 of Fig. 7.

Fig. 11 is a sectional detail taken on line 11—11 of Fig. 5.

Fig. 12 is a sectional detail taken on line 12—12 of Fig. 5.

Fig. 13 is a detail section taken on line 13—13 of Fig. 7.

Fig. 14 is a sectional detail taken on line 15 14—14 of Fig. 2, with parts in elevation.

As shown in the drawings,

The locking mechanism is incased in a metal casing comprising a rear section of channel shape, denoted by the reference numeral 1, and having side attaching flanges 2, integral therewith, and a flat cover plate 3, is provided with longitudinal protuberances 4, formed therein, said cover plate being adapted to be secured over the channel casing plate 1, and attached therewith as a unit upon a door 5, shown in Fig. 1, which is hinged in a door frame 6. Secured in parallel arrangement, perpendicularly upon the inner surface of the channel casing member 1, and extending longitudinally thereof, are a pair of guide bars 7 and 8, respectively, which extend outwardly beyond the casing member 1, affording attaching eye-plates 9, hereinafter described.

Upwardly projecting lugs 10, are formed along the upper edge of the respective guide members 7 and 8, which engage through apertures in the cover plate 3, as clearly shown in Fig. 2, to assist in holding the same properly located upon the channel casing member 1. A bottom slide plate denoted as a whole by the reference character "A," is slidably mounted against the inner surface of the channel casing member 1, with a portion thereof slidable between the guide members 7 and 8, and is provided with a slot, in register with an aperture 12, which is formed in the channel casing member 1.

Disposed flat against the inner surface of the casing member 1, as clearly shown in Fig. 3, is a tiltable latch plate "B," and a relatively large circular aperture 13, is provided therethrough adapted to receive fitted therein a circular eccentric 14, formed on a handle stud or shaft 15, which is journaled through registering apertures provided in the cover plate 3, and the casing member 1, respectively. A hand wheel 16, is secured upon the upper squared end of the handle shaft or stud 15, as clearly shown in Figs. 2 and 14.

Slidably mounted over the respective plates "A" and "B," is another plate denoted as a whole by the reference character "C," 65 which has a rectangular aperture 17,

through which projects a latching tooth 18, formed on one end of the tiltable plate "B." Said slidable plate "C," is provided with a downward lug or stop 19, which projects into the rectangular space formed between the end 20, of plate "A" and the catch member "B," said projection 19, extending beyond the surface of plate A.

Said plate "C," at one side thereof, is provided with a long flat bar or rod extension 21, clearly shown in Fig. 6, which extends slidably between upwardly projecting guide lugs 22, formed upon the bottom slide plate "A," and has coiled therearound a compression spring 23, bearing at one end against said lugs 22, and at its other end against a washer 24, pinned at the end of said flat bar extension 21. Thus said plates "A" and "B," are constrained to slide together except for the relative movement allowed therebetween to further compress the initially stressed compression spring 23.

Formed upon the handle stud or shaft 15, is a geared segment 25, and at one side thereof is a shoulder or stop 26. Said slidable plate "C," is provided with an extension 27, the edge of which forms a stop for the shoulder 26, as clearly shown in Figs. 6 and 8. For the purpose of tilting the plate "B," for instance, from the position shown in Fig. 6, to that shown in Fig. 7, a pin projection 28, is formed thereon adapted to be contacted by one of the teeth of the gear segment 25, when the handle is turned beyond the initial release position shown in Figs. 6 and 7.

Slidably mounted within the casing at one side thereof, disposed above and slidably upon an extension of the plate "A," is a rack bar 29, which, as clearly shown in Figs. 5 and 6, is slidable between the side wall of the channel plate 1, and the edge of the plate "C," as well as the guide member 7. The teeth on this rack member 29, are in mesh with the teeth of the gear segment 25, so that actuation of the hand wheel 16, must cause movement of the rack bar 29. Movement of the rack bar 29, is resisted by a coiled spring 30, bearing against one end thereof, and against a stop 31, secured in the channel casing 1. Said channel casing 1, is struck outwardly as clearly shown in Figs. 9 and 14, at two points, denoted by the reference numeral 32, corresponding with the protuberances 4, (shown in Fig. 2) of the cover plate 1, to afford longitudinal recesses 120 for the respective springs 23 and 30.

As clearly shown in Figs. 2 and 4, a cylindrical tube 33, extends between the eye members 9, and is pivotally connected therein by a semi-cylindrical pintle 34, the other end of said tube 33, having sliding telescoping engagement with a rod 35, which extends therewith and is pivoted upon a bracket 36, on the door frame, as clearly shown in Fig. 1. As shown in Fig. 2, the inner end 130

of said telescoping rod 35, has threaded thereinto a bolt 37, the end of which is slotted to receive one end of a flexible metal strap 38, engaged therein and held secured by a pin 39. Said steel strap extends along the flat side of the semi-cylindrical pintle 34, and inwardly between the guide members 7 and 8, respectively, of the latch casing, disposed above the slide plate "A", and extending at its end slidably beneath the slide plate "C". The inner free end of the strap element 38, is provided with an inclined edge 40, and also a notch 41, said inclined edge 40, adapted to strike the latch 18, to swing the same outwardly against the resistance of the spring 23, resulting from the cam action of plate "B" against the end of plate "A", as shown in Fig. 8, permitting the same to thereafter engage in the recess 41, as shown in Fig. 6. Said steel strap member 38, is also provided with a series of apertures 42, therethrough, for the purpose of locking said strap in different fixed positions in the lock casing by means hereinafter described.

A stiffening plate 43, is secured upon the under surface of the cover plate 3, as shown in Fig. 14, and fitted through an aperture in said cover plate and its plate 43, is an upright tubular member 44, held rigidly in position and provided with a cylindrical vertically movable pin 45, the lower end of which is reduced in diameter to engage through the apertures 42, of the strap, as well as the aperture 12, in the channel casing member 1.

Coiled around said locking pin 45, is a spring 46, bearing upwardly against the top wall of the tubular member 44, and downwardly against a collar or washer 47, held upon the locking pin 45, by a pin 48. The top surface of the tubular member 44, is notched to receive a handle or finger piece 49, seated therein, which is formed integral with the locking pin 45, to hold the locking pin in the retracted position shown in Fig. 14. Said tubular member 44, is also slotted at right angles to the notched portions thereof, permitting said finger piece 49, to slide downwardly therein when said finger piece 49, is rotated through an angle of 90 degrees, thus permitting projection of the locking pin through the apertures 42 and 12.

The operation is as follows:

Assume first the door upon which the lock is mounted is in open position and the operation is in the direction of locked position. The spring 30, is under compression and is so held by the stop 27, being in engagement with the projection 26, on the gear segment 25.

As the door is swung toward closed position, the flexible strap 38, which is pivotally connected upon the door jamb, slides inwardly through the lock casing between guide members 7 and 8, and plates "A"

and "C"; and the inclined or mitered edge 40, of the inner free end of said strap contacts with the latch 18, as shown in Fig. 8, tilting the latch outwardly, against the pressure being exerted by the spring 23, the plate "B" pivoting upon the eccentric 14, which is integral with the gear segment 25.

As the strap 38, continues its forward movement, the free end thereof strikes against the lug 19, on the slide plate "C", moving said plate inwardly together with the spring connected slide plate "A".

Thus far in the operation, the spring 30, is still held under tension as the end 27, of plate "C", has not been carried beyond the stop 26, on the gear segment 25. Before it is moved completely out of engagement with the stop 26, the catch 18, of the latching member "B" is brought into register with the notch cut in the end of the strap and through the action of spring 23, causes the innermost end of plate "A" to move into forcible contact with the offset on plate "B" (as shown in Fig. 3) the catch 18, being moved into the slot in the strap. As the door is further closed, consequent movement of the flexible strap breaks the engagement between the stops 26 and 27. The spring 30, now being free, operates on the rack bar 29, rotating the eccentric 14, shown in Figs. 13 and 14, so that the parts assume the position shown in Fig. 5; the movement of the eccentric, in connection with the latch member "B", having produced a pulling stress drawing and fastening the door tightly closed.

It will be seen that the pressure between the door and jamb, caused by the movements described, will be dependent upon the adjustment of the bolt 37, shown in Fig. 2, in the sliding member 33, in its relation with the force exerted by the spring 30, through the gear and eccentric mechanism employed.

It will further be seen that when the parts are in the locked position shown in Fig. 5, not only has the stress been carried considerably beyond the dead center of the eccentric, thus insuring a positive fastening, but that the lower edge of the locking member "B" has, by the throw of the eccentric, been brought into contact with the flange of the lock casing, so by no means aside from operating the handle for the purpose, can the catch 18, be removed from the notch 41, in the strap and the door released.

In order to unlock the door, the hand wheel 15, of the lock, is rotated in a direction toward the hinged side of the door and the following series of operations take place: The rack bar 29, is retracted against the compression of its spring 30, and the movement of the eccentric 14, relieves the tension stress upon the tiltable plate "B". The spring 23, which is interconnected to plates "A" and "B" and initially stressed under

compression, being now unrestricted, moves plate "C" over so that its end 27, passes beneath stop 26, on the gear segment 25, immediately the latter is moved above it and the parts are thereby held against reverse motion. The parts have now taken the positions shown in Fig. 6: The catch on plate "B" is still held firmly in the notch in the flexible strap so that the door, though free from tension, remains securely fastened. Further movement of the handle brings one of the teeth of the gear segment 15, into contact with the pin 28, projecting from the catch plate "B", and by the rocking motion imparted throws the catch 18, out of the notch in the flexible strap releasing the door, as shown in Fig. 7. The handle is then released and a backward movement brings the surfaces 26 and 27, into full contact and the spring 80, is thus held under compression.

It will be seen that it is impossible to open the door without setting the mechanism for the next closing and that when the door has been opened, the parts can not be changed from that position without closing the door.

I am aware that various details of construction may be varied through a wide range without departing from the principles of this invention, and I therefore do not propose limiting the patent granted otherwise than necessitated by the prior art.

I claim as my invention:

1. In a door lock of the class described, a flexible strap member connected to the door frame, in sliding engagement with the door, a locking device for said strap member mounted upon the door through which said strap member slidably extends, latching means within said mechanism to automatically interlock with said strap as it moves through said mechanism due to closing of the door, and spring stressed means released by continued movement of said strap after latching thereof to draw the same under tension into said mechanism to hold the door tightly closed.

2. In a locking device for doors, means mounted upon the frame having a sliding connection with the door, a casing mounted upon the door through which said means slidably extend, a movable latch within said casing adapted to latch with the inner end of said means as the door is swung toward closed position, and spring stressed mechanism released thereafter to shift said latch into close adjustment with said means to tension said means and draw the door tightly closed.

3. In a locking device for doors of the class described, means pivoted upon the frame having a sliding connection with the door, a casing secured upon the door with which said means has sliding engagement, a tiltable latch within said casing adapted to interlock with a notch in the end of said

means, a handle member, means holding the same rotated into a position at rest against spring tension, and mechanism released by said slidable means to permit the movement of the handle member and shift said latch into close engagement with said slidable means to tension the same as the door is swung closed.

4. In a locking device of the class described, a flexible strap pivoted upon a door frame, a casing member mounted upon a door hinged in said frame through which said strap slidably extends, a handle member rotatably mounted in said casing, a circular eccentric thereon, a tiltable plate engaged with said eccentric, a latch on said plate to interlock with a notch in the end of said strap as the strap moves into the casing with a closing movement of the door, and resilient mechanism interconnected with said handle released for movement after locking of said latch with said strap to tension the strap by said latch member due to the shifting of said tiltable plate by the eccentric to draw the door tightly closed in the frame.

5. A device of the class described comprising in combination with a door hinged in a frame, means pivoted on the frame and having sliding relation with the door, locking mechanism for said means mounted on the door comprising a latch to interlock with said means and resiliently operating mechanism to shift said latch to stress said means under tension after latching of said means to swing the door tightly closed in its frame.

6. The combination with a door hinged in its frame of locking means mounted upon the door, a member mounted upon the frame having sliding engagement therewith, a latch forming a part of said means to interlock with said member as it is projected through said means, and mechanism released by continuous movement of said member to shift said latch under spring tension and stress said member to draw the door tightly closed in its frame.

7. In a door lock of the class described, a member connected to the door frame and in sliding engagement with the door, a locking device for said member mounted upon the door through which said member slidably extends, latching means within said mechanism to automatically interlock with said member as it moves through said mechanism due to closing of the door, spring stressed means released by continued movement of said strap after latching thereof to draw the same under tension into said mechanism to hold the door tightly closed, and a rotatable handle to stress said means and move the same into position to unlock the door.

8. In a locking device for doors, means mounted upon the frame slidably relatively of the door, and a casing mounted upon the door through which said means slidably ex-

- tends, a movable latch within said casing adapted to latch with the inner end of said means as the door is swung toward closed position, spring stressed mechanism released 5 thereafter to shift said latch into close adjustment with said means to tension said means and draw said door tightly closed, and a handle to actuate said means into position under spring stress to unlock the door.
10. 9. In a locking device for doors of the class described, means pivoted upon the frame for the door, a casing secured upon the door with which said means has sliding engagement, a tilttable latch within said casing 15 adapted to interlock with a notch in the end of said means, a handle member, means holding the same rotated into a position at rest against spring tension, mechanism actuated by said slidable means to release the handle 20 member and shift said latch into close engagement with said slidable means to tension the same as the door is swung closed, and auxiliary mechanism to interlock with said slidable means to lock the door in either 25 open or closed position.
10. In a locking device of the class described, an apertured flexible strap pivoted upon a door frame, a casing member mounted upon a door hinged in said frame, through 30 which said strap slidably extends, locking mechanism mounted on the casing adapted to interlock with said strap by engagement with one of the apertures therein, a handle member rotatably mounted in said casing, an 35 eccentric thereon, a tilttable plate pivotally engaged with said eccentric, a latch on said plate to interlock with a notch in the end of said strap as the strap moves into the casing with a closing movement of the door, 40 and resilient mechanism interconnected with said handle released for movement after locking of said latch with said strap to tension the strap by said latch member due to the shifting of said tilttable plate by the eccentric to draw the door tightly closed in the 45 frame.
11. A device of the class described comprising in combination with a door hinged in a frame, flexible means pivoted on the 50 frame and having sliding relation with the door, locking mechanism for said means mounted on the door comprising a latch to interlock with said means due to movement of said means inwardly, resiliently operating mechanism to shift said latch to stress said means under tension after latching of said means to swing the door tightly closed in its frame, and an auxiliary locking device for interlocking with said flexible means in 55 dependent of said latch to lock the door open or closed.
12. The combination with a door hinged in its frame, of locking means mounted upon the door, a member mounted upon the frame 60 having sliding engagement therewith, a locking member mounted on the locking means to lock said slidable member in different positions, a latch forming a part of said means to interlock with said member as it is projected through said means, and mechanism released by continuous movement of said member to shift said latch under spring tension and stress said member to draw the door tightly closed in its frame. 70
13. In a locking device of the class described a member hinged to the door frame, latching mechanism secured to the door adapted to engage the member to close the door and mechanism for automatically actuating the latching mechanism to exert a 80 tension on the hinged member to draw the door tightly shut. 75
14. In a locking device for doors coacting latching members one pivoted to the frame and the other pivoted to the door and 85 adapted to engage each other as the door is closed and a tension mechanism for automatically actuating one of said latching members to tension the other to tightly close the door. 90
15. In a locking device for doors coacting latching members one pivoted to the frame and the other pivoted to the door and adapted to engage each other as the door is closed, a tension mechanism for automatically actuating one of said latching members to tension the other to tightly close the door and a manually operated mechanism for disengaging said latches and setting the tension mechanism. 95
16. A locking device for doors comprising interlocking relatively slidable members, one pivoted to the door and the other to the frame adapted upon closing the door to interlock and a tension mechanism adapted to force one of the members to slide the other locking member relatively thereof to firmly hold the door closed. 100
17. A locking device for doors comprising interlocking relatively slidable members, one pivoted to the door and the other to the frame adapted upon closing the door to interlock, a tension mechanism adapted to force one of the members to slide the other locking member relatively thereof to firmly hold the door closed and a manually operated mechanism for releasing the tension of said interlocking members and disengaging the same and also for setting the tension mechanism. 110
18. A locking device for doors comprising coacting locking members, one pivoted to the frame and one to the door, automatic mechanism for actuating one locking member to tension the other and means for engaging one of said locking members and holding the door in any open position. 115
19. In a door lock a casing, an apertured member slidable therein, a latch for engaging said member, mechanism for automati- 120
- 125
- 130

- cally actuating the latch to tension said apertured member and a bolt for engaging in any of said apertures to firmly hold the door in any open position.
- 5 20. A door lock comprising a casing, a resilient member extending thereinto, a latch member, a spring pressed rack bar, a toothed wheel adapted to engage the rack bar to compress the spring, a cam movable there-
10 with, means on said latch member adapted to be engaged by the wheel to release the latch as the spring is compressed and means for holding the wheel from rotation to retain said spring compressed.
- 15 21. A door lock comprising a casing, a resilient member extending thereinto, a latch member, a spring pressed rack bar, a toothed wheel adapted to engage the rack bar to compress the spring, a cam movable there-

with, means on said latch member adapted 20 to be engaged by the wheel to release the latch as the spring is compressed, means for holding the wheel from rotation to retain said spring compressed and mechanism for automatically releasing the last named means 25 to permit the compression spring to automatically actuate the toothed wheel and cam to actuate the latch to exert a tension on the resilient member to firmly hold the door closed.

30 In testimony whereof I have hereunto subscribed my name in the presence of two subscribing witnesses.
